Attorney

UNITED STATES PATENT OFFICE.

JOHN S. SANDERS, OF BEGGS, OKLAHOMA.

VACUUM OIL TREATER.

Application filed May 19, 1926. Serial No. 110,235.

This invention relates to pumps and more particularly to deep oil well pumps.

One of the important objects of the invention is the provision of means associated with the gas anchor pipe for separating the water entering with the oil therefrom during the operation of the working valve.

Another object of the invention is the provision of a nipple of a lesser diameter than the gas anchor pipe and the entrance pipe connected with the lower end of the nipple whereby when the liquid is forceably drawn through the nipple the water will be caused to separate from the oil.

15 A further object of the invention is the provision of means for connecting the nipple, entrance pipe and gas anchor pipe together whereby these parts will be efficiently connected and spaced from the tubing anchor pipe at all points to permit the free flow of the liquid around the gas anchor pipe, nipple and entrance pipe.

With these and other objects in view, the invention consists in the novel construction, 25 arrangement and formation of parts, as will be hereinafter more fully described, claimed and illustrated in the accompanying drawings in which a preferred embodiment of the invention is shown.

30 Figure 1 is a side elevation of the improved device,

Figure 2 is a central longitudinal section through the same,

Figure 3 is a horizontal section taken on line 3—3 of Figure 1, looking in the direction of the arrows, and

Figure 4 is a horizontal section taken on line 4—4 of Figure 1 looking in the direction of the arrows and illustrating the arrangement of the nipple within the tubing anchor pipe.

Referring to the drawings in detail, wherein similar reference characters designate corresponding parts throughout the 45 several views, the numeral 5 designates the lower end of the barrel of the usual pump to which is connected by means of a collar 6, the depending tubing anchor pipe 7. In accordance with this invention the lower end 50 of the pipe 7 is closed by a suitable cap 8. Directly below the coupling collar 6, the tubing anchor 7 is provided with a plurality of entrance openings 9 for permitting the flow of the oil into the same.

55 The collar 6 at a point between the barrel 5 and the tubing anchor 7 is provided with

an internal annular flange 10 provided with a seat 12 for the reception of the lower tapered end 13 of the standing valve casing 14. This casing 14 is provided with a valve seat 15 on which is adapted to normally rest a ball valve 16. The upper end of the casing 14 has connected therewith the usual 60 garbutt rod 17 for permitting of the connection thereof to the working valve, whereby the standing valve can be conveniently pulled when necessary.

The lower end of the casing 14 is internally threaded for the reception of the upper end of the gas anchor pipe 18 which extends centrally into the tubing anchor pipe 7. The gas anchor pipe 18 extends below the entrance openings 9 and in accordance with this invention has connected thereto an elongated nipple 19 by a suitable coupling 70 collar 20. The bore of the nipple 19 is of a considerable lesser diameter than the gas anchor pipe 18 for a purpose which will be hereinafter more fully described.

The lower end of the nipple 19 has connected thereto, by a suitable coupling 21, an entrance pipe 22 which is of a greater internal diameter than the bore of the nipple 19. It is preferred that the internal diameter of the entrance pipe 22 be the same 80 as the internal diameter of the gas anchor pipe 18. In actual practice, in one use of the device, a nipple having a three-eighths inch diameter will be used in conjunction with gas anchor pipes and entrance pipes 90 having a diameter of three-fourths of an inch.

In operation the oil and water will flow into the anchor tubing 7 and will gravitate to the lower end thereof. The operation of 95 the working valve will cause a suction or vacuum in the nipple 19 and owing to the decreased diameter of the nipple 19 over the gas anchor pipe 18 this suction will be considerably increased. The oil and water 100 will be drawn into the entrance pipe 22, thence into the nipple 19 and then into the gas anchor pipe 18. The rush of the liquid in the nipple 19 will cause the separation 105 of the oil and water and these ingredients are then carried to the surface in the ordinary manner.

Changes in detail may be made without departing from the spirit or the scope of this invention.

I claim:

1. In an oil well pump, the combination

with a barrel for receiving the working valve, a tubing anchor depending therefrom, a standing valve, and a gas anchor pipe depending from the standing valve into the tubing anchor, of a nipple of lesser diameter than said gas anchor pipe connected therewith.

2. In an oil well pump, the combination with a barrel for receiving the working valve, a tubing anchor depending therefrom, a standing valve, and a gas anchor pipe depending from the standing valve, of a nipple of lesser diameter than said gas anchor pipe connected therewith, and an entrance pipe 15 of greater diameter than the said nipple connected with the lower end of the nipple.

3. In an oil well pump, the combination with a barrel for receiving the working valve, a tubing anchor depending therefrom, a standing valve, and a gas anchor pipe depending from the standing valve and communicating with the casing thereof, of an oil and water separator connected with the gas anchor pipe at the lower end thereof 25 including means for contracting the liquid

prior to the entrance thereof into the gas anchor.

4. In an oil well pump, the combination with a barrel, a tubing anchor connected therewith and depending therefrom, a cap closing the lower end of the tubing anchor, said anchor having a plurality of liquid entrance openings adjacent to the upper end thereof, a standing valve arranged in the barrel adjacent to the lower end thereof, and a gas anchor pipe extending axially into the tubing anchor below the entrance openings thereof and communicating with the casing of the standing valve, an elongated nipple detachably connected with the lower end of the gas anchor pipe and having an internal diameter lesser than the internal diameter of the gas anchor pipe, and an entrance pipe of substantially the same internal diameter as the gas anchor pipe connected with the lower end of the nipple and terminating adjacent to said cap.

In testimony whereof I affix my signature.

JOHN S. SANDERS.
